UNITED STATES PATENT OFFICE.

GILMORE M. YOST, OF CLEVELAND, OHIO, ASSIGNOR TO THE COLUMBIAN HARDWARE COMPANY, OF CLEVELAND, OHIO, A CORPORATION OF OHIO.

VISE.

1,298,145.

Specification of Letters Patent. Patented Mar. 25, 1919.

Application filed August 17, 1916. Serial No. 115,362.

To all whom it may concern:

Be it known that I, GILMORE M. Yost, a citizen of the United States, residing at Cleveland, in the county of Cuyahoga and State of Ohio, have invented a certain new and useful Improvement in Vises, of which the following is a full, clear, and exact description.

This invention relates to vises, and particularly wood workers' vises. The invention has particular reference also to what is known as quick-acting or quick-release vise, and also to the so-called universal vise, the jaws of which can be positioned or adjusted to various positions with respect to the bench or other support on which the vise is mounted, and the movable jaw of which can be adjusted by the screw or can be released and slid in or out relative to the normally stationary jaw.

The principle object of the invention is to provide certain improvements which render the vise more efficient and durable, and also to improve the jaw-adjusting means, particularly the mechanism by which the adjusting screw and its associated nut are engaged or released so as to permit either the regular screw adjustment or the quick sliding movement of the movable jaw.

The invention may be briefly summarized as consisting in certain novel details of construction and combinations and arrangements of parts which will be described in the specification and set forth in the appended claims.

In the accompanying sheets of drawings, wherein I have shown two slightly different forms of my invention: Figure 1 is a top plan view with the vise detached from the bench and with the supporting bracket for the brace rod in section; Fig. 2 is a side elevation of the same with the bench shown in outline; Fig. 3 is a vertical sectional view, the section being taken substantially centrally and longitudinally through the vise attached to the bench, this view showing by dotted lines the vise jaws tilted to a position at an angle to their normal position; Fig. 4 is a transverse sectional view substantially along the line 4—4 of Fig. 3 looking in the direction indicated by the arrow. Fig. 5 is a front view with the operating handle in section substantially along the line 5—5 of Fig. 3 looking in the direction indicated by the arrow; Fig. 6 is a plan view

with parts in section showing the major portion of a vise embodying a slight modification of my invention; Fig. 7 is a view looking toward the front jaw of Fig. 6 with the front cap removed and with the operating handle in section substantially along the line 7—7 of Fig. 6 looking in the direction indicated by the arrow.

Referring now to the drawings, and first to Figs. 1 to 5 inclusive, 10 and 11 represent the two jaws of the vise, the latter being the front jaw and being movable toward and from the former, and both being simultaneously movable in a variety of directions, as will be explained.

The exact construction or shape of the jaws is a matter of no consequence, their adjacent faces being preferably flat and both being preferably provided with endwise movable dogs 12 in which, however, I claim no novelty herein.

In order that the vise may be attached to a support such as a bench 13 I utilize a hinge, including a leaf or stationary hinge member 14, which is designed to be attached to the top face of and to extend over the front edge of the bench, and a second hinge member 15 which is hinged or pivoted to the first by means of a horizontal pin or equivalent securing device 16. The hinge member 15 which normally projects downwardly is provided with an annular split sleeve or hub 17 which is normally beneath and at the front edge of the bench as shown in Fig. 2. This annular support or split sleeve which is designed to be loosened or tightened by means of a movable clamp lever 18 receives a cylindrical extension or boss 19 projecting rearwardly from the rear or inner jaw 10.

Secured to the front jaw 11 and extending through the relatively stationary jaw 10 is a pair of guide rods 20 which pass through bearing openings in the jaw 10 and its cylindrical extension 19 and at their rear ends are held a predetermined distance apart by a connecting yoke or cross piece 21 (see particularly Fig. 1). Between these guide rods 20 is a threaded adjusting screw 22 which turns in but moves longitudinally with the front jaw and has a bearing in the rear cross piece or yoke 21. The front end of the screw is provided with the customary rotary handle 23.

In order that the front jaw may be moved

toward and from the relatively stationary rear jaw when the screw is turned, I provide in the cylindrical extension 19 of the rear jaw a nut or nut segment 24 which is held from endwise movement and also from rotary movement in the cylindrical extension, so that when the handle 23 is turned the screw and front jaw 11 travel inwardly or outwardly.

- 10 One of the novel features of the invention resides in the means for effecting the quick release by which nut and screw may be disengaged at the will of the operator, so that the front jaw can be slid inwardly or outwardly toward and from the relatively fixed jaw 10 without turning the handle. The means for thus releasing the nut from the screw or for causing the nut to disengage the screw includes a rather long cam shaft 25, 20 which at its front end is connected with the front jaw and has a sliding engagement with the rear jaw, this shaft being just beneath the screw, as shown in Fig. 4. This shaft, which is substantially the length of the screw and guide rods 20 has a section or segment removed for nearly its entire length so as to present or form a flat surface, and it is so disposed relatively to the nut that if it is turned so that the flat face is next to the nut the nut may drop away from the screw or threaded shaft, a spring being preferably employed to shift the nut from the screw in the event gravity can not be relied on for this purpose, but when the shaft is 30 turned through about $\frac{1}{4}$ turn so that the round portion of the shaft engages the nut, it lifts the nut upwardly and holds it in engagement with the screw. In this case the spring which moves the nut away from the screw is in the form of a wire 26 which extends through the nut and has its ends entering into the wall of the cylindrical extension 19 of the rear jaw 10. When the nut is 40 pressed upwardly by the cam shaft this spring is put under tension so that when the shaft is turned so as to release the nut the spring will immediately pull the nut from the screw. In order that the nut may be quickly and conveniently released from the screw the rod 25 which projects a distance beyond the front jaw is provided at its outer end with a finger 27 which is turned in a counter clockwise direction, as viewed in Fig. 5, to release the nut and is returned to 50 normal position when released so as to cause the nut to be carried back into engagement with the screw by a spring 28 which surrounds the forward portion of the cam shaft (see particularly Fig. 3). 55
- 60 If it is desired to simultaneously turn both jaws about the axis of the feed screw this can be done by loosening the split collar 17 by means of the clamp lever 18. If it is desired to tilt both jaws relatively to the bench about the axis of the hinge this

can be readily done. One position of the jaws when so tilted is shown by dotted lines in Fig. 3. In order that the jaws may be held tightly in any position to which they may be tilted, I provide a brace rod (see 70 Figs. 1 and 2) which at its forward end is provided with a head 31 pivotally connected by a screw or bolt 32 to the cylindrical split clamp 17, this brace rod likewise passes through a split sleeve 33 pivotally supported 75 on a bracket 34 which extends downwardly from the lower side of the bench, as shown in Figs. 1 and 2. By means of a clamping lever 35 this split sleeve can be caused to clamp the rod 30 at any point thereof, or 80 by loosening the same the rod can be slid through the sleeve. To tilt the jaws the sleeve is loosened so as to permit the jaws to be tilted to the proper position, the rod 30 at such time sliding through the sleeve 85 and when the jaws are in proper position the sleeve will be tightened onto the rod 30 by the clamp lever 35, whereupon the jaws will be held firmly in the position to which they have been moved. 90

In Figs. 6 and 7 I have shown a construction which is like that first described, except that an additional adjustment is provided, this adjustment being the tilting of the front jaw relative to the rear so that the 95 adjacent jaw faces can be caused to assume a position tapered or inclined relative to each other instead of the normal parallel relation.

In order that this may be accomplished 100 the front jaw here designated 11^a is pivoted by means of a pin or equivalent pivoting device 40 to a head 41 to which the forward ends of the guide rods 20 are secured and in which the screw has a bearing as in the first 105 instance. This head 41 is forked as shown particularly in Fig. 7, and extending into the fork from the jaw 11^a is a rib-like extension 42 which is rigid with the jaw. Journaled in this rib 42 is an adjusting screw 43 110 which passes through a nut 44 in the form of a cylindrical pin which is movable lengthwise of the shank of the adjusting screw in a slot 45 of the rib extension 42. The ends of this nut or cylindrical pin 44 extend into 115 a suitable slot of the fork of the relatively stationary head 41 so that when the adjusting screw is turned this nut which travels along the screw tilts the jaw 11^a relatively to the stationary jaw 10, as will be readily 120 understood by reference to Figs. 6 and 7. The head and the adjacent portions of the movable jaw 11^a are preferably inclosed in a cover 46 through which the head of the adjusting screw 43 projects. 125

With the construction shown in Figs. 1 to 5, the jaws can be tilted to any desired position; they can be turned to any desired position relatively to the axis of the feed screw, and the two jaws can be relatively 130

adjusted by means of the screw, or the front jaw can be slid independently of the screw toward and from the rear jaw by releasing the nut from the screw. The mechanism is 5 convenient to operate and at the same time the construction is strong and durable in all respects. In addition to the adjustments of which the construction shown in Figs. 1 to 10 5 is susceptible the vise may be given the adjustment shown in Figs. 6 and 7 by which the front jaw can be tilted relatively to the rear jaw without in any way affecting the other adjustments, it being understood that the vise shown in Figs. 6 and 7 will be provided 15 with the quick-acting mechanism including the nut release which is precisely like that first described, and that the jaws will be mounted so that they may be tilted or turned precisely as in the first instance.

20 Having thus described my invention, I claim:—

1. In a vise, a pair of clamping jaws including a normally stationary and a relatively movable jaw, a feed screw connected 25 to the relatively movable jaw, a normally stationary nut normally engaging the screw and movable toward and from the same, means for causing the release and engagement of the nut and screw comprising a rotary cam shaft extending from the relatively movable jaw past the relatively stationary jaw and in proximity to said nut, a guide extending from the relatively movable jaw, an annular support, and an annular 30 member on the relatively stationary jaw having a bearing in said support whereby both jaws, feed screw guide and shaft may be simultaneously turned in said support, said nut being located in said annular member, and the feed screw, cam shaft and guide 35 extending through said annular member.

2. In a vise, a pair of clamping jaws including a normally stationary and a relatively movable jaw, a feed screw and a guide 45 connected to the relatively movable jaw, a normally stationary nut normally engaging the screw and movable toward and from the same, means for causing the release and engagement of the nut and screw comprising a rotary cam shaft extending from the relatively movable jaw past the relatively stationary jaw and in proximity to said nut, an annular support, and an annular member 50 on the relatively stationary jaw having a bearing in said support whereby both jaws, feed screw guide and shaft may be simultaneously turned in said support, said annular support being pivotally connected to a bench securing device whereby the vise may 55 be tilted, said nut being located in said annular member, and said feed screw, guide and cam shaft extending through said annular member.

60 3. In a vise, a pair of clamping jaws including a rear normally stationary jaw, and

a front relatively movable jaw, a feed screw and a guide both connected to the relatively movable jaw, a normally stationary nut normally engaging the screw and movable into and out of engagement with the same, means 70 for causing the release and engagement of the nut and screw comprising a rotary cam shaft extending from the front jaw through the rear jaw and alongside said nut, a spring acting on said nut to cause the disengagement 75 of the screw and nut when the shaft is turned to a certain position, an annular bearing for the vise, and an annular projection on the rear jaw rotatably supported in said bearing whereby both jaws, feed 80 screw guide and cam shaft may be turned relatively to the bench or other support for the vise, said nut being located in said annular projection and said feed screw, guide and cam shaft extending through said annular projection.

4. In a vise, a pair of clamping jaws including a normally stationary rear jaw and a relatively movable front jaw, a feed screw and a guide both connected to the relatively 90 movable jaw, a normally stationary nut normally engaging the screw and movable into and out of engagement with the same, means for lifting the nut into engagement with the screw and for permitting the nut to move 95 out of engagement therewith, comprising a shaft which moves with the front jaw and extends therefrom through the rear jaw and alongside the nut, said shaft having a flat face for substantially its entire length, an 100 annular bearing for the rear jaw, an annular projection on the rear jaw received in said annular bearing and a clamping means associated with said annular bearing whereby the jaws, screw guide and shaft may be 105 turned in the bearing and may be tightened or clamped in any adjusted position, said nut being located in said annular projection, and said screw, guide and cam shaft extending through said annular projection. 110

5. In a vise, a normally stationary rear jaw and a relatively movable front jaw, a screw connected to the front jaw with which it may be adjusted, a nut engaging the screw and normally fixed relatively to 115 the rear jaw, means for effecting quick release of the front jaw, comprising a shaft having a segment removed therefrom forming a flat face, said shaft being journaled in the front jaw extending therethrough and through the rear jaw in proximity to 120 and past said nut, a handle in front of the front jaw for turning said shaft in one direction, and a spring connected with said shaft for turning the same in the reverse direction, an annular support for both jaws whereby they may be turned relatively to a bench or other support, a guide connected with the front jaw, said nut being located within said annular support, and said screw, 125 130

4
shaft and guide extending through said annular support.

6. In a vise, a pair of hinged or pivoted members, one adapted to be secured to a bench or the like, an annular split bearing connected on one of said hinged members, a pair of jaws including a normally stationary rear member having an annular projection extending into said split bearing, a relatively movable front jaw, a screw connected with the front jaw and extending through said bearing, a nut normally engaging the screw and normally stationary relatively to the rear jaw and bearing, said nut being located within the said bearing, a cam shaft extending parallel with the screw and projecting from in front of the front jaw through both jaws and the bearing and in proximity to the nut, and a guide secured to the front jaw and extending through the rear jaw and bearing parallel to the screw, said guide having a bearing in the rear jaw.

7. In a vise, a pair of hinged or pivoted members, one adapted to be secured to a bench or the like, an annular split bearing connected on one of said hinged members, a pair of jaws including a normally stationary rear member having an annular projection extending into said split bearing, a relatively movable front jaw, a screw connected with the front jaw and extending through said bearing, a nut normally engaging the screw and normally stationary relatively to the rear jaw and bearing and located within the latter, a cam shaft extending parallel with the screw and projecting from in front of the front jaw through both jaws and the bearing and in proximity to the nut, and a pair of guide rods secured to the front jaw and extending through the rear jaw and bearing parallel to the screw and cam shaft. 25 30 35 40

In testimony whereof, I hereunto affix my signature.

GILMORE M. YOST.
